United States Patent Office.

GARRETTSON SMITH AND HENRY BROWN, OF PHILADELPHIA, PENNSYLVANIA,
ASSIGNORS TO ABBOTT AND NOBLE, OF SAME PLACE.

Design No. 3,591, dated July 27, 1869; antedated June 29, 1869.

DESIGN FOR THE PLATES OF A STOVE.

The Schedule referred to in these Letters Patent and making part of the same

To all whom it may concern:

Be it known that we, GARRETTSON SMITH and HENRY BROWN, of Philadelphia, county of Philadelphia, State of Pennsylvania, have originated a new Design for the Plates of a Stove; and we do hereby declare that the accompanying drawing, and following explanation thereof, form a full, clear, and exact description of the said design.

In the drawing, the figure represents the plates of the stove, A being the base, which is composed of the bottom plate *a*, the opposite side plates *b*, (ornamented as shown,) the front plate *c*, with its two ornamental doors, and the upper plate *d*, the whole being supported on legs *e*.

B is the top plate of the stove, having the ornamental edging clearly shown in the drawing, and terminating at the top in an ornamental projection, *D*.

We claim the design for the plates of a stove, substantially as described, and as represented in and by the accompanying drawing.

In testimony whereof, we have signed our names to this specification, in the presence of two subscribing witnesses.

GARRETTSON SMITH.
HENRY BROWN.

Witnesses:

JOSEPH A. READ,
HARRY SMITH.
